ADDISON C. FLETCHER M. D. OF NEW YORK, N. Y.

Letters Patent No. 76,734, dated April 14, 1868; antedated April 3, 1868.

GRATE-BAR.

The Schedule referred to in these Letters Patent and making part of the same.

TO ALL WHOM IT MAY CONCERN:

Be it known that I, ADDISON C. FLETCHER, M. D., of the city, county, and State of New York, have invented a certain new and useful Improvement in Grate-Bars, of which the following is a full, clear, and exact description, reference being had to the accompanying drawing forming part of this specification, and in which—

Figure 1 represents a vertical longitudinal section of a grate-bar constructed according to my improvement.

Figure 2, a vertical transverse section of the same, or a pair thereof, through the line $z z$ in fig. 1; and

Figure 3, a plan of a few or series of such grate-bars arranged in connection with each other.

Similar letters of reference indicate corresponding parts.

My invention has for its object the combustion, in a fireplace or furnace, of inflammable gases in their escape to the chimney, by the introduction of heated atmospheric air through perforations in a bridge or rise in rear of the fuel, and the nature of my invention, in this connection, consists in a novel construction of grate-bars, preferably of a tubular character in direction of their length, and with a valve or valves to control the admission of air at their outer ends, said or other suitable bars terminating in cylindrical formations, constituting, when the several bars are in their place, a transverse bridge-like tubular structure, of a perforated character on its upper surface, covered by a perforated coating of fire-clay or brick-work, through which heated air, say, the air heated in its passage through the tubular grate-bars, escapes, to burn the carbonic oxide into carbonic acid, producing what may be termed a second burning in the furnace.

Referring to the accompanying drawing, A represents the longitudinal portion of the bars, preferably made double, so far as their tubular construction or arrangement of air-passages $a a'$ through them is concerned, having open spaces b between the two portions of them, forming the double structure, and lugs or dividing projections c outside of them, to form spaces d between them and the adjoining bars. These longitudinal tubular portions A are provided, at their outer ends, with a valve or lid, or valves or lids B, whereby atmospheric air may be excluded from or admitted to, in a controllable manner, the passages $a a'$, and said longitudinal portions A being furthermore constructed or provided, and terminating in open communication with, at their inner ends, transverse cylinders C, of a bridge-like character relatively to the longitudinal portions of the bars, and cast with or forming part of them, so that the insertion of the one portion in its place involves or includes the proper arrangement and connection of the other. These cylinders C are arranged end by end, to form a continuous transverse tubular bridge, and may be supplied with heated air from its end or ends, but this may be unnecessary where the longitudinal portion A of the bar is hollow, and air supplied to the cylinders C by the passages $a a'$. In the upper surfaces of said cylinders C are perforations d , in communication with apertures e , made in or through a fire-brick or other similar covering, D.

On starting the fire, the lids or valves B should be closed, so as not to interfere with the draught, but after ignition has been fairly established or the fire in full blast, said lids are opened more or less, according to requirements, as regards the combustion of the gases, which introduces air through the passages $a a'$, that, as it traverses therethrough, is heated by the exterior exposure of the longitudinal portions A, on their upper surfaces and sides bound by the openings $b d$, and, entering the cylinders C, is further heated thereto, as it emerges therefrom through the apertures $d e$, by reason of the location and comparatively close construction of said cylinders and their fire-brick covering D, which, being a slow conductor, serves to retain the heat communicated to it by the passage of the flame and heated gases over it. In this way is the air introduced to or over the fire at the bridge in a highly-heated condition, producing a more perfect combustion of the escaping inflammable gases, the bridge and fire-bars proper, as represented in the drawing, both contributing to this result, and both formed of one or the same piece, in the construction of the grate-bar or bars. To clean out said cylinders of matter lodging therein, the same may be provided with lids or doors s , or openings covered by lids or doors, may be made in the brick-work, at the ends of the tubular structure formed by said cylinders.

I do not claim a hollow grate-bar, nor a hollow perforated bridge, *per se*; but

What I claim as my invention, and desire to secure by Letters Patent, is—

1. A grate-bar, having cast to or forming part of it, in the rear, a perforated cylinder C, having an annular projection on one side, and a corresponding recess on the other, the axial line of which cylinder is arranged transversely to the length of the bar, the same forming, in connection with the other bars of like construction, a tubular perforated bridge, for the passage of heated air to the fire, substantially as specified.

2. The application to a grate-bar, constructed substantially as described, of a longitudinal tubular portion, A, terminating in a transverse cylindrical perforated structure, C, of bridge-like character, and made to form part of the grate-bar of an outside lid or valve, B, essentially as and for the purpose or purposes herein set forth.

ADDISON C. FLETCHER, M. D.
